UNITED STATES PATENT OFFICE

136,540

DESIGN FOR AN AIRPLANE ENGINE

Lloyd M. Taylor, San Leandro, Calif.

Application December 23, 1941, Serial No. 104,815

Term of patent 14 years

To all whom it may concern:

Be it known that I, Lloyd M. Taylor, a citizen of the United States and a resident of the city of San Leandro, county of Alameda, State of California, have invented a new, original, and ornamental Design for an Airplane Engine, of which the following is a specification, reference being had to the accompanying drawing forming a part thereof.

The single drawing is a perspective view of an airplane engine showing my new design.

The airplane engine of my design is substantially symmetrical about its horizontal axis.

I claim:

The ornamental design for an airplane engine, as shown, and described.

LLOYD M. TAYLOR.
